OTHER PUBLICATIONS

Three Photographs of Container Provided by Applicant in use in the United States on or before Mar. 1, 2014 (Exhibit A).

Primary Examiner — Janice Patyk

(74) Attorney, Agent, or Firm — King & Partners, PLC

(57) **CLAIM**

The ornamental design for a container spout, as shown and described.

DESCRIPTION

FIG. 1 is a front perspective view of a container spout, showing our new design.

FIG. 2 is a top plan view of the container spout of FIG. 1; and,

FIG. 3 is a bottom plan view of the container spout of FIG. 1.

The broken lines in the figures illustrate the portions of the design that form no part of the claimed design.

1 Claim, 2 Drawing Sheets---
